UNITED STATES PATENT OFFICE.

ALEXANDER CLASSEN, OF AIX-LA-CHAPELLE, GERMANY.

SODIUM SALT OF IODIN COMPOUND.

SPECIFICATION forming part of Letters Patent No. 618,167, dated January 24, 1899.

[Application filed June 1, 1898, Serial No. 682,280. (No specimens.)

To all whom it may concern:

Be it known that I, ALEXANDER CLASSEN, of the Technical High School of Aix-la-Chapelle, a citizen of Germany, and a resident at 5 Templergraben No. 57, Aix-la-Chapelle, in the Kingdom of Prussia, Germany, have invented new and useful Improvements in the Manufacture of New Iodin Compounds and the Resulting Products, (for which I have obtained 10 the following Letters Patent in foreign countries: Great Britain, No. 12,987, dated July 4, 1894; Luxemburg, No. 2,221, dated January 18, 1895; Italy, Reg. Gen., Vol. XXIX, No. 38,079, and Reg. Att., Vol. LXXIV, No. 374, 15 dated March 31, 1895; Norway, No. 4,466, dated January 22, 1895, and No. 4,467, dated July 29, 1895; Portugal, No. 1,958, dated September 19, 1895; Brazil, No. 1,916, dated September 3, 1895; British India, No. 610, dated 20 February 23, 1895; Sweden, Nos. 7,132 and 7,134, dated January 25, 1895; Denmark, No. 767, dated October 2, 1895, and Germany, Nos. 85,929 and 85,930, dated May 26, 1895, No. 86,069, dated July 22, 1895, and No. 88,390, 25 dated May 14, 1896,) of which the following is a specification.

This invention relates to the production of the sodium salt of an iodin compound containing the iodin in the benzene nuclei of phenolphthalein.

In carrying my invention into effect I first produce tetraiodophenolphthalein, which is described and claimed in an application heretofore filed by me on 29th day of October, 30 1894, Serial No. 527,113. I will, however, here first describe some of the processes for producing tetraiodophenolphthalein before proceeding with the description of the processes for producing the sodium salts thereof. Iodin 35 derivatives of phenols have already been produced in great number. I have discovered that new iodin compounds are obtainable, which are also capable of pharmaceutical application, if the phenolphthalein is treated in a 40 suitable manner with iodin or substances yielding iodin.

According to my investigations the phenolphthalein can be readily converted into iodin derivatives by solution in alkalies, addition of iodin and precipitation of the products by means of acids. The iodin com-

pounds thus obtained differ from the iodin derivatives hitherto produced from the oxy-bodies by the fact that by the entrance of all the iodin bodies into the benzene nuclei the 55 hydrogen atoms of the hydroxyl groups remain free and give the resulting compounds the character of strong acids. The iodin derivatives of aromatic oxy-bodies hitherto produced in alkaline solution are, without 60 any exception, insoluble in alkalies, and the reason of this insolubility consists in the presence of iodin oxyl-compounds. The proof that in the case of the iodin derivatives of phenolphthalein all the iodin atoms are in the nuclei 65 consists not only in their acid nature, but also in the tetricmetrical determination of the number of the hydroxyl groups, from which it resulted that in the case of the iodin compounds obtained their number is always equal 70 to that of the original matters. Another proof of this position is their behavior in the presence of acetic anhydrid. While it has been shown that the iodin compounds of phenolphthalein are converted by boiling for 75 several hours on the reflux cooler with acetic anhydrid into corresponding (triaceto) compounds, which by boiling with soda-lye are reconverted into the original iodin compounds, 80 the action of the acetic anhydrid on halogen-oxyl compounds takes place in quite a different manner. Either the iodin contained in the hydroxyl groups is separated with the formation of an acetyl derivative, containing correspondingly less iodin atoms, or the iodin 85 atoms are transposed into the nucleus. Moreover, all the halogen-oxyl compounds are completely insoluble in alkalies and show only little resistance. On the contrary, the iodin compounds of the phenolphthalein substituted in the nucleus can be treated with 90 boiling soda-lye without decomposing them. The acid nature enables them, moreover, to form salts with light and heavy metals.

The iodin can be employed either dissolved 95 in a solution of potassium iodid or in any other suitable solvent or it may be employed in the form of iodids with the addition of agents capable of liberating iodin—for instance, chlorid of lime, chlorin, bromin, or 100 the like.

According to my researches the electric cur-

rent can also be used more profitably in order to liberate iodin from the iodids. Iodin-chlorid, or the combination of iodin, chlorid, and muriatic acid or the like agents, can be used in place of iodin for producing the iodin compounds from the said hydroxyl products or secondary amins or the like. The production of the iodin compounds hereinbefore defined is illustrated by the following examples.

10 The parts are by weight.

Process for Preparation of Tetra-iodo-phenol-phtalein.

(a) *Under cooling.*—Thirty grams phenol-phtalein are dissolved in one hundred grams water containing forty grams sodium hydrate. To this is added a solution of one hundred grams iodin and one hundred and twenty grams potassium iodid in four hundred grams water, the temperature of which must not exceed 20° centigrade. The red color of the alkaline phenolphtalein solution is during this process changed into a deep blue. The solution is then well cooled and cooled hydrochloric acid is added. An amorphous yellowish-brown body is precipitated, which, by thoroughly washing with a solution of potassium, iodid, and water, can be perfectly purified. If the moist precipitate is raised to a higher temperature, (about 100° centigrade,) it is converted into a white body—namely, tetraiodophenolphtalein—while the yellowish-brown body produced in the cold is to be considered as tetraiodophenolphtalein plus one molecule of water. It is purified by solution of the undried precipitate in chloroform and precipitation with ligroin, and after drying *in vacuo* it is obtained as a yellow powder devoid of odor and is perfectly permanent in light and air. The analysis gives:

Calculated for $C_{20}H_{10}I_4H_{20}$
 $I=60.4$ per cent.; found $I=60.05$ per cent.

45 The conditions as to solubility and other properties agree with those of the white tetraiodophenolphtalein, which is at once obtained.

(b) *By heating.*—If after adding the iodin 50 the deep-blue solution be heated for some time on a steam-bath, the color changes into a yellowish-brown tint. If hydrochloric acid be added a gray-white body is precipitated, which by thoroughly washing or also by dissolving 55 in soda-lye and precipitating with acids is obtained in a white condition as tetraiodophenolphtalein. It must therefore be assumed that with the body produced in the cold and having an additional molecule of water the 60 lactone formation is destroyed. In the same way that the yellow body can be converted into the white the reverse operation can be effected. If the white tetraiodid of phenolphtalein is dissolved in the cold in soda-lye 65 and hydrochloric acid is added, undercooling, the first-described yellow body is precipi-

tated. After heating with soda-lye until the color changes the white compound is again obtained by means of hydrochloric acid.

The tetraiodophenolphtalein is insoluble in 70 water and ligroin. In the other organic solvents, under heating, it is easily soluble, but with greater difficulty in the cold. It is most readily taken up by warm chloroform. It is insoluble in acids; readily soluble in alkalies. 75 It is distinguished by perfect absence of odor, and it is quite permanent when exposed to light and moisture.

The analysis gives the formula: $C_{20}H_{10}I_4O_4$

Per cent. Per cent. Per cent.
Calculated $I=61.7$ $C=29.21$ $H=1.22$
Found $I=61.92$ $C=29.23$ $H=1.53$

Electrolytical production.—30 grams phenolphtalein are dissolved in one hundred 85 grams water containing thirty-five grams sodium hydrate. To this are added one hundred and forty grams potassium iodid in two hundred grams water, and it is subjected to electrolysis for some hours with a current of 90 about 1.5 amperes. The change of color shows the end of the reaction. It is then heated until the blue tint has changed into brownish yellow, and the tetraiodophenolphtalein is precipitated with hydrochloric 95 acid.

Having thus described the various methods of producing tetraiodophenolphtalein, I will now proceed to describe the process for the production of the sodium salts thereof.

The tetraiodophenolphtalein is first dissolved in water containing the calculated quantity of sodium hydroxid, (one-tenth of the employed tetraiodophenolphtalein) and the solution is evaporated to dryness. The 105 salt thus obtained represents, dried at 100°, a blue powder very easily soluble in water with a blue color; with more difficulty in alcohol. It corresponds to the formula:

The sodium salt here described is used as a sprinkling-powder in the case of purulent sores, particularly in the case of soft chancres. In aqueous solution it is employed for moist bandages and tampons at a concentration 120 of two per cent. For rinsing the bladder in bladder catarrh a solution of two per cent. has given very excellent results. For healing diseases of the throat and ear a solution of from 0.1 to 0.5 per cent. is employed for 125 gargling and rinsing. The sodium salt is also used as first material in the production of various metallic salts of tetraiodophenolphtalein—as, for instance, aluminium, zinc, lead, iron, and manganese salts.

130 What I claim as new, and desire to secure by Letters Patent, is—

As a new article of manufacture, the sodium salt of an iodin compound containing the iodin in the benzene nuclei of phenolphthalein, the same being a dark-blue amorphous powder, nearly odorless and tasteless and readily soluble in water, glycerin and alcohol.

5 In testimony that I claim the foregoing as

my invention I have signed my name in presence of two subscribing witnesses.

ALEXANDER CLASSEN.

Witnesses:

JOHN HECKMANNS,
F. M. BRUNDAGE.
